DAVID M. MEEKER, OF NEWARK, NEW JERSEY.

APPARATUS FOR MELTING AND APPLYING SEALING-WAX, &c.

SPECIFICATION forming part of Letters Patent No. 600,619, dated March 15, 1898.

Application filed November 28, 1896, Serial No. 613,763. (No model.)

To all whom it may concern:

Be it known that I, DAVID M. MEEKER, a citizen of the United States, and a resident of Newark, Essex county, State of New Jersey, have invented a new and useful Apparatus for Melting and Applying Sealing-Wax, &c., of which the following description, taken in connection with the drawings herewith accompanying, is a specification.

- 10 Heretofore it has been the usual practice in applying sealing-wax, gums, and other similar material upon letters, packages, bottles, &c., for the purpose of sealing the same to hold the sealing material above the article to be sealed and then apply heat to the same with a match or taper until it has become sufficiently melted to drop upon the article to be sealed. This practice is objectionable for many reasons. For instance, applying the
- 15 flame directly to the wax or other sealing material tends to discolor the same, and this, upon letters or other articles where the attractive appearance is an important feature, is very undesirable. Another objection to the above practice is that after heating the wax it is very difficult to regulate with any degree of accuracy the amount that will fall or drop upon the article to be sealed, and in case the amount is more or less than required
- 20 an insufficient or unattractive seal results. Further, such described practice requiring the use of both hands, more or less time is consumed in laying aside the wax and taper preparatory to applying the seal, during which time the wax is liable to become so cooled as not to receive a proper impression or seal thereon. To avoid such described and other equally obvious objections to the practice or method referred to, and in so doing provide
- 25 means whereby the wax or other sealing material may be melted and automatically applied in a clean, rapid, and economical manner without the direct application of the flame to the sealing material, has been the object of my present invention.

In carrying my invention into effect I provide a bar or piece of metal, of copper or other suitable material, to form a good heat-conductor, to which heat is adapted to be applied at some desired point and having a recess or receptacle formed therein to receive the wax or

sealing material to be melted, which said recess or receptacle is provided with a restricted discharge-orifice therein, through which the sealing material may pass to the article 55 to be sealed after becoming sufficiently melted by contact with the heated surface or walls of the said receiving-recess. By this means heat may be applied to the bar or piece containing the recess at some convenient point 60 distant from the latter and the heat be conducted therethrough to the wall of said recess, so that a piece of sealing-wax or other similar material may be placed in the latter and be contained therein on account of its re- 65 stricted exit-orifice until it becomes sufficiently melted to pass through the latter and drop in a liquid form upon the article placed in position to receive the same, after which a seal may be applied thereto, if so desired. 70

Referring to the drawings, Figure 1 represents a side elevation of an apparatus embodying my invention in vertical section, and Fig. 2 represents a top view of the apparatus.

To explain in detail, *a* represents a sup- 75 porting stand or holder upon which, as herein illustrated, the heat-conductor *b* is supported. This part *b*, which may be formed of copper, iron, aluminium, or other good heat-conducting material as may be found 80 in practice to be most desirable, is, as herein shown, provided with an enlarged portion *b'* at one end thereof, having a recess or opening *b''* extending vertically through the same. This opening *b''* is enlarged at its mouth 85 or upper end, so as to conveniently receive a piece of wax or other sealing material, and is restricted at a point *b'''* below its mouth, so as to form a recess or receptacle in the upper part of the opening in which the wax re- 90 ceived therein will be contained and held until it has become thoroughly melted, after which it can pass through the said restricted portion *b'''* of the opening and drop upon the envelop or other article placed thereunder, 95 as shown in Fig. 1.

As the melted wax drops upon the letter or other article placed to receive the same, it has a tendency to spread evenly in a circular form, as will be understood; but in order to 100 insure the wax taking the desired form to receive the seal thereon, after the wax has

dropped upon the article being sealed, the latter may be held close to the under side or surface b^4 of the part b' and given a slight movement thereunder, so as to cause the melted wax to be spread and take the form as given by the outline of surface b^4 , as will be obvious. Such being the fact, it will be readily understood that the lower surface or edge of the part b' may be made circular, 10 oval, or in other desired forms, and the wax be caused to take a like form by holding the article close thereto and giving the same such slight movement as may be necessary to properly spread the same. Another feature of 15 this construction is the said lower surface of the part b' being heated keeps the wax sufficiently melted while held in contact therewith as to insure its proper spreading.

The restricted portion b^3 of the opening b^2 20 is formed at a point above the lower end of the latter, as clearly shown in Fig. 1, and the wall of said opening below said restricted portion is flared or tapered outwardly toward its lower end, so as to form an enlarged escape-orifice below the restricted portion b^3 , as 25 shown. The result secured by reason of the wall of the opening b^2 being thus tapered outwardly below the restricted portion b^3 is as follows: After the wax has become thoroughly 30 melted, so as to pass through the restricted portion b^3 , the tendency of the same is to follow the surface of the wall of the opening, as will be obvious, and the said wall being tapered outwardly, as described, will thus cause 35 the melted wax to spread out after passing through the restricted portion b^3 and be evenly distributed upon the article placed to receive the same. The melted wax being thus evenly spread out or distributed to take such form 40 as may be given by the outline of the surface b^4 , as before described, insures its receiving a good impression or seal.

The heat-conductor b , as herein illustrated, 45 is provided with an enlarged heating-surface c at that end opposite its wax receiving and discharging end b' , under which, as herein shown, a small alcohol-lamp d is placed to apply heat thereto. This heating end or surface c is circular in outline and dish-shaped 50 on its under side, so as to afford an increased heating-surface and to better retain the heat. It will be obvious, however, that such heating-surface may be of any desired form or size, as may be found to be most desirable in 55 practice, without departure from my invention.

I have shown the lamp d as a convenient means for applying heat to the conductor b ; but I do not wish to be understood as confining myself to a lamp or any other particular 60 means for such purpose, as any suitable means for applying heat to the said conductor b is within the spirit of my invention. For instance, it may be more convenient in some 65 cases where the apparatus is used more or less continuously to support the part b upon

a bracket secured to the wall or other object in lieu of to the stand, as shown, with its melting end b' extending in a convenient position for use and its opposite end extending 70 to some point adjacent to a gas-burner or other means for applying heat thereto.

It will thus be understood that having illustrated my invention as embodied in one practical form I do not wish to limit myself to 75 such form, as it will be obvious that the construction and arrangement of the several parts may be materially modified as may be found necessary in practice to adapt the apparatus for the different purposes for which it might 80 be used or to the different places where it might be located.

The conductor b is preferably insulated from its holder or stand a by suitable insulating material a' , so as to prevent the con- 85duction of heat to said holder or stand, whereby the latter may be grasped, if so desired, to move the device and also to avoid any damage to the table or other object upon which the holder may be supported or se- 90cured.

Having thus set forth my invention, what I claim as new, and desire to secure by Letters Patent of the United States, is—

1. A heat-conductor, for the application of 95 wax or other sealing material, having a receptacle formed with a delivery aperture in its bottom adapted for the application thereto of the paper or article to be sealed, said conductor being adapted to have heat applied 100 thereto at a point distant from said aperture, substantially as and for the purpose set forth.

2. A heat-conductor, for the application of wax or other sealing material, having a receptacle formed with a delivery-aperture in 105 its bottom, said aperture being adapted to form the outline of the seal, and adapted for the application thereto of the paper or article to be sealed, said conductor being adapted to have heat applied thereto at a point distant 110 from said aperture, substantially as and for the purpose set forth.

3. A heat-conductor of suitable material, provided with an opening therein to receive wax or other sealing material to be melted, 115 having a restricted discharge-orifice through which the melted wax is passed, and provided with an enlarged surface for the application of heat thereto at a point distant from said wax receiving and discharging opening there- 120 in, substantially as and for the purpose set forth.

4. A heat-conductor of suitable material, having means to receive and hold wax or other sealing material to be melted and automatically discharge the same after being melted, and a stand or holder having an insulated connection with said heat-conductor and adapted for supporting the same with a part thereof in position for the application of heat 125 thereto, substantially as and for the purpose set forth.

5. A heat-conductor of suitable material, provided with an opening therein to receive wax or other sealing material to be melted, having a restricted discharge-orifice through which the melted wax is passed, and provided with a concave surface for the application of heat thereto at a point distant from said wax.

or sealing material receiving and discharging opening therein, substantially as and for the purpose set forth.
